FIG. 4 A

INVENTOR.

Alexander Brownlee

UNITED STATES PATENT OFFICE.

ALEXANDER BROWNLEE, OF SAN DIEGO, CALIFORNIA.

REINFORCED CONCRETE CONSTRUCTION FOR PIERS, BULKHEADS, SEA WALLS, AND DRY DOCKS.

1,414,620.

Specification of Letters Patent. Patented May 2, 1922.

Application filed August 3, 1917. Serial No. 184,292.

To all whom it may concern:

Be it known that I, ALEXANDER BROWNLEE, a citizen of the United States, residing at San Diego, in the county of San Diego and State of California, have invented certain new and useful Improvements in Reenforced Concrete Construction for Piers, Bulkheads, Sea Walls, and Dry Docks, of which the following is a specification.

10 My invention relates to improvements in the construction of piers, dry-docks, bulkheads, sea-walls, caissons, coffer-dams and the like structures of reenforced concrete, and the principal objects of my invention are, first, to provide a structure of this type which is composed of comparatively indestructible materials; second, to provide such a structure in the building of which the materials from the place in which the structure 20 is to be erected may be used in connection therewith for reenforcing the structure; third, to provide a structure of the type which may be driven into the bottom of a river, sea, harbor or other place where the structure is to be erected without a prior or special preparation therefor; fourth, to provide a structure of the kind to which the fender or buffer system of any kind may be attached, if desired; fifth, to provide a structure of the kind that is provided with a hollow, monolithic continuous reenforced concrete cap, and sixth, to provide such a structure that is economical of construction and durable.

35 With these and other objects in view, as will hereafter appear, my invention consists of certain novel features of construction, combination and arrangement of parts as will be hereinafter described in detail and particularly set forth in the appended claim, reference being had to the accompanying drawings and the characters of reference thereon which form a part of this specification, in which:

45 Figure 1 is a plan view of my structure for piers and bulkheads, with a portion of the top broken away to better illustrate the location of certain supporting members; Fig. 2 is a vertical sectional view through Fig. 2 in Figure 1; Fig. 3 is a front elevational view of the portion of the structure shown in Fig. 1; Figures 4 and 4^A are cross-sectional views of sheet piling construction showing the form of construction and attachment of the piles to each other for a

water-tight wall; Fig. 5 is a plan view of a portion of a sea-wall constructed along the lines of my invention, Fig. 6, is a vertical sectional view of same through C—D in Fig. 5; Fig. 7 is a cross-sectional detailed view of a part of my pier construction showing a vertical section of the hanging fender and the method of attaching the same to the pier; Fig. 8 is a vertical sectional view of a modification of the structure shown in Fig. 6, and Figure 9 is a part sectional view of a dry well for dry-dock walls.

Similar characters of reference refer to similar parts throughout the different views.

The principal part of my construction are 70 the manholes 1, piles 2, cap 3, fender piles 4, grout chamber 5, longitudinal chamber 6, bracket 7 and hanging girder 8.

The structure of bulkheads, sea-walls, dry-docks or similar devices consists of two or 75 more rows of concrete piles 2. The piles 2 in each of the rows are fitted to one another as shown best in Figs. 4 and 4^A, and when so placed the chamber 5 is filled with grout thereby making a water-tight wall. The 80 rows of piles 2 are set parallel to each other and the space 9 between the rows is filled with sand or other material which may be pumped from the bottom of the bay or ocean, if desired. This filling is accomplished by 85 passing the material through the manholes 1. The rows of piles 2 may be placed vertically, as shown in Fig. 2, or may be inclined as shown in Figs. 6 and 8. The piles 2 are strengthened by reinforcements 11 and 90 each is provided with a longitudinal chamber 6 adapted to have a jet of water forced through for sinking the pile and also to be used to force grout to the bottom of the pile if it is desired to do so for any purpose. 95

On the tops of the piles 2 connecting the parallel rows of said piles 2 is placed a reinforced cap 3. This cap 3 is provided with proper reinforcements, is rectangularly shaped, and is provided with a rectangular 100 chamber therein and all of the parts thereof are thoroughly and strongly reenforced in the usual manner.

A hanging girder portion 8 extends beyond the row of piles 2 and is supported by 105 bracket portions 7 disposed at intervals along the cap member 3. The hanging girder portion 8 is adapted to support the floor portion of the cap and also to have mounted thereon the fender piles 4. By the 110

structure shown of the cap 3 there is provided a hollow monolithic, continuous, reinforced concrete cap that securely binds together the several rows of piles, thus providing a maximum of strength, rigidity and resistance to withstand the weight, stresses and pressures the structure will be called upon to sustain.

If desired, a floating kick-log 14 may be placed against the fender piles 4 to distribute the shock from boats or other causes.

A continuous wale-piece 13 is mounted on the piles 4 adjacent to the piles 2 and each of said piles 4 are securely bolted thereto, and mounted on the wale-piece 13 are chocks 12 which fit between the piles 4 and help to retain them in their proper positions on the wale-piece 13.

The fender piles 4 are of wood and are embedded at their lower ends in the soil or bottom 10, and being attached at their upper ends to the girder 8, are adapted to spring back and forth when pressure is brought to bear against them.

Girders 15 cast integrally with said cap 3 may be used when necessary to strengthen and give greater support to the floor of said cap 3.

In bulkhead construction the outer row of piles 2 are necessarily much longer than the inner row or rows, owing to the fact of a greater length being required to drive to a proper depth for holding them securely, and by the method of reenforcing used the outer part of the piles 2 are of a sufficient thickness of concrete to prevent the reenforcing from being injured by the action of the water.

The monolithic cap 3 is secured to the piles 2 by imbedding the heads of said piles 2 in said cap 3, and by having reenforcing rods of a suitable size imbedded in the grout in the recesses 5 and passing through the parallel side of the said cap 3. The recesses 5 are filled with cement grout after the piles 2 are installed in proper position and when same becomes hardened produces water-tight joints.

The manholes 1 are placed at suitable distances in the cap 3 and are of a sufficient size to allow the chambers 9 to be filled in solidly with sand, gravel or stone, which is preferably done by pumping this material into place from the bed of the harbor or other place where the bulkhead is constructed. By this structure a bulkhead is formed that is practically solid throughout and is indestructible by wave or water as well as by the striking of heavy vessels against it.

The longitudinal chamber 6 in each of the piles 2 enters the pile near the top from the side so as not to interfere with the driving of the pile.

The preferable construction in a sea-wall is to set two rows of piles 2 so that their

upper ends incline at an angle toward each other, as shown best in Fig. 6; otherwise the construction is the same as that already detailed, and if necessary a double row of piles may be driven to form the outer wall, and the space between the two rows filled with concrete where extra strength is needed. Owing to the inclination of the wall the force of the waves on the structure will be very materially lessened.

After three or more piles are driven in place for the further construction, a pair of waling pieces are bolted near the top of the piles and a similar pair near the water-line to form guides to keep the piles in alignment while installing them.

If desired the tops of the rows of piles can be anchored together by struts cut in between the top wale pieces, and for that purpose the bolts holding the top wale pieces to the sides of the piles have an eye in place of a head. These eye-bolts should be nearly opposite each other and the rows are connected by rods having hooks on the ends and a turn-buckle in the middle to take up the stress on the struts.

After a sufficient number of piles are in place, usually about ten or more, the forms for the cap 3 are erected on the top of the upper waling pieces and when the form is completed and the reenforcing rods placed, the concrete is poured in the forms and when the concrete is sufficiently hardened the forms are removed and moved along the line of the piling, and the process of re-enforcing and filling is thus repeated until the entire wall is constructed, thus causing the said cap portion to be continuous throughout.

In cases where it is desired to fill the vacant space included between the rows of piling and the cap and the space in the cap, this filling in may be done as soon as sufficient of the cap has been constructed, and, if necessary, a temporary wall across the end of any particular section to be filled may be erected for the purpose of holding the filling and allowing the water to escape therefrom as the fill is made.

It will be noticed that by this method of construction it is not necessary in any case to construct a coffer-dam in order to erect a structure of this kind.

Having thus described my invention, what I claim as new and desire to secure by Letters Patent, is:

A bulkhead, sea wall, dry-dock, and the like, comprising parallel impervious walls formed of concrete sheet piles jetted and driven into the bottom of a body of water, forming a hollow channel between said walls, a hollow, monolithic, reenforced concrete cover of substantial depth and formed with a comparatively large enclosed chamber and comparatively small filling holes

through its upper floor and lower floor, cast about the upper ends of the piles forming said walls and forming integral enclosing walls therewith, and a filling of plastic dredging detritus injected through the filling holes into the hollow channel formed

5 between said walls and into the enclosed chamber in said cover, the whole forming a rigid and massive structure.

ALEXANDER BROWNLEE.
